UNITED STATES PATENT OFFICE

172,029

CARTON SETUP AND CLOSING MACHINE

Al Johnson, Stockton, Calif.

Application October 23, 1952, Serial No. 21,960

Term of patent 14 years

(Cl. D55—1)

To all whom it may concern:

Be it known that I, Al Johnson, a citizen of the United States, residing in the city of Stockton, county of San Joaquin, State of California, have invented a new, original, and ornamental Design for a Carton Setup and Closing Machine, of which the following is a specification, reference being had to the accompanying drawing, forming a part hereof.

Figure 1 is a perspective view of the front and one side of a carton set up and closing machine showing my new design;

Figure 2 is a perspective view showing the top and other side thereof; and

Figure 3 is a rear perspective view thereof.

I claim:

The ornamental design for a carton setup and closing machine, substantially as shown.
